UNITED STATES PATENT OFFICE

2,274,613

REFRIGERATION APPARATUS

Ernest B. Miller, Annapolis, Md., assignor to
William Burnet Wright, Baltimore, Md.

Application March 4, 1939, Serial No. 259,921

5 Claims. (Cl. 62—91.5)

The present invention relates to a refrigerating apparatus and also to a vending machine in which the articles to be vended must be held at a particular temperature, usually less than atmospheric temperatures and often at temperatures low enough to preserve frozen products in the condition best suited to commercial requirements. In apparatuses of this type and particularly vending machines employing solid carbon dioxide as the refrigerating medium, one of the main defects has been what is termed "frosting." This is particularly objectionable in vending machines since articles to be vended are often frozen together and furthermore such frosting interferes with the structural parts of the machine and the operation of the mechanical parts.

One of the principal objects of the invention is to eliminate frosting so as to protect the mechanical and structural parts of the machine and prevent the freezing together of the articles to be vended.

The preferred form of the invention relates to the type of apparatus wherein solid carbon dioxide rests on a fixed plate. A metal contactor plate is movable into and out of contact with said fixed plate, such movement being controlled by a thermostat. Heat transfer members are disposed in the space to be refrigerated and means is provided to conduct heat from the members to the contactor plate.

Another object of the invention is to provide an improved form of heat conductor for transferring heat from the heat transfer members or member to the contactor plate.

Another object of the invention is to provide a vending machine designed to insure maximum intervals of time between servicings with the refrigerant, as such servicing constitutes one of the main operating expenses. One charge of 50 pounds of solid carbon dioxide will maintain the machine of the present invention at about 10° F. for a period of from 4 to 7 days.

Another object of the invention is to provide a carefully regulated control over the temperature of the merchandise being vended so that such articles as ice cream may always be in a condition permitting immediate consumption by the customer.

A further object of the invention is to provide a vending machine with a plurality of magazines to accommodate a variety of articles such as ice creams of different flavors and so arranged that the customer can readily select the desired article.

Other objects and features of novelty will be

apparent from the description taken in connection with the drawings in which

Fig. 1 is a vertical section through one embodiment of the invention.

Fig. 2 is a horizontal sectional view taken substantially on the line 2—2 of Fig. 1 and looking in the direction indicated by the arrows.

Fig. 3 is a plan view of the contactor plate and conductors.

Fig. 4 is a perspective view of one of the conductors, and

Fig. 5 is a perspective view of another form of conductor.

Referring to the drawings which illustrate the invention as embodied in a vending machine, 10 indicates an outside container very thoroughly insulated and supported on the members 11. It will be noted that this container also has its bottom and top walls thoroughly insulated and, as shown in Fig. 2, is substantially octagonal in plan view. Supported on a vertical shaft 12 extending through the bottom wall of the outer container is a turntable 13 carrying a number of magazines 14 supported on the table by the brackets 14' and vertical rods 15. The present invention is illustrated as adapted for a machine vending ice cream in cups 16. These cups are arranged in vertical columns and carried by the magazines 14. There are a plurality of them arranged in a circular series, as shown in Fig. 2. The different columns may comprise cups carrying ice cream of different flavors. Of course, other articles could be arranged in a similar manner. The turntable 13 may be rotated by means of the gearing 17 and 18, shaft 19 and hand wheel 20 so as to bring any magazine opposite the vending outlet. Fitted to the bottom of each magazine is a tripper mechanism 21 actuated by the horizontal movement of cam 22 when the door 23 is moved to its open position. It will be understood that the tripper 21 supports the column of cups. At the top of the container 10 there is provided a hatch 24 for charging the magazines.

Disposed within the columns of cups is a second container 25 supported in any suitable manner from the top of the first container and having a bottom 26. Within this container is a shell 27 and having a fixed metal bottom 28 adapted to support solid carbon dioxide or the like 29. In order that this second container may be charged with the solid refrigerant, a removable insulated hatch 30 is provided. Immediately under the fixed metal bottom is a metal contactor plate 31 movable into and out of contact with the fixed bottom. For this purpose the contactor

plate is pivoted at 32 to one end of a bell crank lever 33 pivoted at 34. The vertical leg 35 of this bell crank is connected to the plunger rod 36 of a Sylphon bellows 37 which is in communication with the bulb 38 by means of tube 39. A volatile liquid in bulb 38 exerts variable pressures on the Sylphon bellows according to the temperatures to which the bulb 38 is subjected and thereby moves the thermostat plunger 36 either to the right or left depending on whether the temperature has decreased or increased. This movement through the bell crank is communicated to contactor plate 31. Of course, when contactor plate 31 is out of contact with the bottom 28, there is no heat transfer and vice versa when in contact there is a heat transfer. In this manner the temperature of the space within the container 10, that is the space to be refrigerated, may be controlled.

Disposed vertically just outside the container 25 are the finned heat transfer members 40. These are supported in a suitable manner on the brackets 41 which in turn are in heat transfer communication with the contactor plate 31 through the flexible heat conductors 42. As clearly shown in Fig. 4, these conductors comprise flexible flat metal strips 43 of braided heat conducting metal wire such as copper bent to suitable shape. They are spaced throughout their lengths and fastened together at their ends and provided with the holes 44 and 45 for the cap screws 46 and 47 respectively. As clearly shown in Fig. 3, there are a plurality of these flexible heat conductors.

The heat conductors of the present invention afford a very efficient heat transfer means and being flexible and in spaced strips, offer a minimum of resistance to the movement of the contactor plate in response to the thermostat in the refrigerated space.

It will be noted that the opening 48 through which the rod 36 extends is larger in diameter than the rod thereby providing an unrestricted communication between the two containers that is to say, the solid ice container and the container having a space to be refrigerated. It follows that CO₂ gas evaporated from the solid carbon dioxide can pass from the inner container into the outer container, thereby any atmospheric air present in the refrigerating space or outer container will be displaced by the heavy CO₂ gas so that no moisture is present to cause frosting. Heretofore one of the principal defects in refrigerating apparatus employing solid carbon dioxide has been due to frosting of mechanical parts and/or the articles being refrigerated. In the present instance, if atmospheric air were not eliminated from the space being refrigerated, the cups containing the ice cream might freeze together. It will be noted that the contactor plate and bottom 28 of the inner container are in an atmosphere of CO₂ gas and so no frosting collects on the same to interfere with an efficient heat transfer. The excess carbon dioxide gas collecting in the outer container may be vented by leaking past the filled hatch 24 or by any other suitable vent at the top of the outer container (not shown). This feature of preventing frosting of the mechanical parts of the apparatus and articles being refrigerated constitutes an important feature of my invention.

The door 23 is mounted on rollers 49 and moves horizontally to control the vending outlet 50. The door 23 may only be opened after latch 51 has been lowered. This may be accomplished by inserting a coin in slide 52 mounted on pivot

53 movable with the door. The shaft 54 is operated by the customer and carries a cam 55. This cam is so constructed that a coin must be present between the same and a finger 56 on the latch 51 in order to effect the lowering of the latter. A slight turning of shaft 54 in a counterclockwise direction effects this lowering when a coin is present. Mounted rigid with shaft 54 is an arm 57 at its free end carrying an arcuate member 58 having an arcuate slot 59 therein, in which is positioned a pin 60 on lever 61 connected to the door at one end and loosely mounted on shaft 54 at the other. The first counterclockwise rotation of shaft 54 frees latch 51. Further rotation of shaft 54 in a counterclockwise direction carries the arcuate member 58 so that pin 60 strikes the right hand end of slot 59 and actuates lever 61 to open the door 23.

Movement of the door 23 causes cam 22, through arms 62 and 63 to move the latch 21 in a direction to release the bottom cup 16 of ice cream. Movement of the latch 21 is effected against the resistance of spring 64 as it carries an upper arm 65 engaging the latter. When the latch 21 moves spring 64 it also moves a pin 66 through the wall of the magazine to hold the next cup from falling down. When the door is closed of course latch 21 returns to its normal position and pin 66 moves to release the cup it is holding.

Fig. 5 illustrates another form of conductor comprising a flexible cable 43' of braided heat conducting wire. This cable at its ends is connected to terminals having holes 44' and 45' respectively.

From the foregoing description it is thought that the operation of the apparatus is clear and that no further explanation is necessary.

It will be noted that the heat conductors 40 shown in Fig. 4 are substantially U-shaped as seen in side elevation and are made up of a plurality of substantially U-shaped superposed flexible strips of braided metal wire spaced from each other through the greater part of their lengths, their free ends being fastened together as by welding.

It is important that the door 23 close the delivery opening so that there will be no leakage of carbon dioxide out by the same, thus admitting air and resulting in possible frosting. It is also important that the door be closed as soon as possible after the delivery of a package, otherwise the heavy carbon dioxide gas will flow out through the delivery opening, be replaced by air, and result in frosting due to the moisture in the air. To eliminate leakage of the carbon dioxide gas, as far as possible, a heavy coil spring 70 is attached at one end to cam member 22 rigid with the door and anchored at its other end to the shell of the outer container. This spring holds the door closed with considerable force thus eliminating leakage of carbon dioxide gas and it also closes the door quickly after the delivery of a package. In order to make a gas tight joint between the door and the container packing 71 may be employed.

Although the form of the invention has been described in detail, it is to be understood that it is not thus limited but includes modifications and changes that come within the scope of the appended claims.

I am aware of Patents No. 1,901,000 and No. 1,937,690 and do not claim anything shown in these patents.

I reserve the right to file a divisional application on the coin control mechanism.

Having fully described my invention, what I claim as new and desire to secure by Letters Patent is:

1. In apparatus of the character described comprising a container having a fixed metal bottom adapted to support solid carbon dioxide, a metal contactor plate movable into and out of contact with said bottom, a thermostat in the space to be refrigerated controlling such movement, and a heat transfer member in the space to be refrigerated, the improvement comprising a flexible heat conductor connecting the plate and member.

2. The improvement according to claim 1 wherein the conductor comprises flat metal strips spaced throughout their lengths and fastened together at their ends.

3. The improvement according to claim 1 wherein the conductor comprises a braided cable.

4. The improvement according to claim 1

wherein the conductor comprises flat strips of braided metal wire spaced throughout their lengths and fastened together at their ends.

5. In apparatus of the character described comprising a container having a fixed metal bottom adapted to support solid carbon dioxide, a metal contactor plate movable into and out of contact with said bottom, a thermostat in the space to be refrigerated controlling such movement, a heat transfer member in the space to be refrigerated, a flexible heat conductor connecting the plate and member, a chamber in which the contactor plate is disposed and means providing communication between the part of the container above the solid carbon dioxide and said chamber whereby all air is displaced from said chamber by carbon dioxide gas evaporating from the solid carbon dioxide and thereby eliminates frosting of the contactor plate and the bottom of the container.

ERNEST B. MILLER.
